UNITED STATES PATENT OFFICE

2,168,806

POWER-TRANSMITTING APPARATUS

John L. Reilly, Claremont, N. H., assignor to Sullivan Machinery Company, a corporation of Massachusetts

Application March 23, 1936, Serial No. 70,229

3 Claims. (Cl. 60—54.5)

My invention relates to power transmitting apparatus, and more particularly to apparatus for transmitting a series of blows to percussively-actuated tools.

5 Ordinarily, pneumatically actuated percussive tools are extremely convenient, but their overall efficiency from the prime mover to the tool itself, is relatively quite low, because of the power lost in the air compressor, in the transmission of the 10 compressed air, and in the use of the air in the tool motor proper. As a result, several times as much power must be delivered by the engine which actuates the air compressor, as ultimately is delivered in the form of effective work to the 15 working implement proper.

With the application of power through a hydraulic column to a percussively actuated implement, an extremely efficient power transmission is possible; and it is an object of my invention to 20 provide an improved percussive tool operating system or apparatus. Another object of my invention is to provide an improved percussive tool operating apparatus, operating on the principle of reciprocating a column of liquid and causing 25 a piston element or its equivalent to move in sequence with said column, moving in advance of said column during the striking operation, and moving in a rearward direction as said column is retracted. A further object of my invention is to provide an improved hydraulic drilling 30 apparatus having improved controlling means. Still another object of my invention is to provide an improved hydraulic drilling apparatus having improved means for transmitting blows 35 of different intensities to a tool. Other objects and advantages of my invention will hereinafter more fully appear.

The basic elements of an illustrative embodiment of my invention include a column of liquid, 40 as for example, oil or water, means for applying pushes to one end of said column, with intermediate reverse movements of said column, and means actuated by the column during the applications of pushes to the latter to effect the 45 delivery of blows at a desired point. Desirably, the means for applying pushes may take the form of a reciprocated pump plunger, and the means for transmitting the blows in the form of a piston moving in a cylinder. Desirably, means is provided for varying the amplitude of the pushes, 50 for example, by increasing the range of movements of the pump plunger. Desirably, means is provided for enabling the interruption of the percussive operation, and this is preferably accomplished by interrupting the percussive op-

eration at a time when the maximum quantity of liquid is stored within the percussive device although obviously other means, as for example, connecting the pumping device with a chamber in which the pump fluid may surge, and concurrently shutting off the communication between the fluid actuated element and the pump element, would accomplish the same function. Desirably, means for ridding the system of any air which may be mingled with the operating 10 liquid will be provided; and if desired, a yielding connection may be arranged at an appropriate point between the prime mover and the pump piston, so that yielding may take place at reasonable times. Cooling may be provided for if 15 necessary due to long-continued operation. If wide variation in amplitude of flow-travel is intended varied length of liquid column may be arranged. Spring, atmospheric or super-atmospheric pressure hammer return is possible. 20

In the accompanying drawing in which an extremely simple illustrative embodiment of my invention is shown:

Fig. 1 is a perspective view of a complete percussive apparatus, herein in the form of a rock 25 drilling apparatus, in which the invention is incorporated.

Fig. 2 is a central vertical section through the power receiving and delivering portion of the apparatus. 30

Fig. 3 is a horizontal section through the crankshaft and pump cylinder of the power delivering portion of the apparatus.

Fig. 4 is a view partially in section, and partially in side elevation of the structure shown 35 in Fig. 3.

Referring to the drawing, it may be observed that Fig. 1 shows a power generating unit, generally designated 1, a power receiving and delivering unit, generally designated 2, and a power 40 transmission connection 3. The power delivering unit 1 is mounted upon an appropriate portable base 4, having wheels 5, and a caster 6, so that the same is readily moved from place to place by a handle, of which a portion is shown 45 at 7. On the platform 4 is a prime mover 8 herein in the form of an electric motor, which is suitably connected with a power transmitting device, generally designated 9, and herein comprising a stationary cylinder 10 mounted upon 50 the platform 4, a piston or plunger 11 reciprocating in the bore 12 of the cylinder 10 and connected by a connecting rod 13 with an adjustable crank pin 14 on a crank disc 15, which is supported in turn by a crankshaft 16 mounted 55

in suitable bearings 17 on the base platform 4. A driving pulley 18 is keyed, as at 19, to the crankshaft 16, and herein a belt 20 connects the driving pulley 21 of the motor 8 with the driving pulley 18 of the crankshaft 16. Any suitable means for adjusting the position of the crank pin 14 radially in the slot 22 in the crank disc 15 may be provided, and I have shown herein, for the purpose of illustration, a purely manual adjustment with appropriate holding means 23. The rear end of the cylinder bore 12 is provided with a combined filling and venting connection 25 having a removable closure element 26, and the rear end of the cylinder bore is connected through the connecting means 3 with the power receiving and transmitting means 2, previously mentioned.

The connecting means 3 may be variously constructed, as for example being in the form of a heavy rubber hose suitably treated to render it resistant to oil and having nearly inflexible walls. Of course, it is possible that the walls of this hose may be made of less flexibility, depending upon the desired results, and it will be obvious that flexible metallic hose can be used if desired, also a hose of rubber, or rubber and canvas, or rubber and cord composition.

The power receiving and transmitting means 2 closely resembles a percussive pneumatic drilling motor, save that the usual distributing valve mechanism is omitted. It comprises here a cylinder 30 having a bore 31 in which a piston 32, provided with a suitable number of sealing grooves 33, is reciprocable. A built-up head construction comprising elements 34 and 35 housed within an outer head and handle member 36 is arranged at the rear end of the cylinder. The member 36 has grasping handles 37 in one of which, in a slot 38, there is pivotally supported a manually movable lever 39, which can be moved to operate a throttle valve 40. A central passage 41 in the member 34 connects, through a radial passage 42 in said member, with a chamber 43 in the member 36, and the chamber 43 is separated by a ported septum 44 from a primary chamber 45 in the member 36, with which the end of the connection 3 communicates. A valve seat 46 surrounds the port in the septum 45, and the conically formed head 47 of the valve 40 is adapted to cooperate with said seat. A spring 48 normally tends to maintain the valve closed, said valve closing towards said connection 3. The valve seat may be scored, or the valve traversed by a pin hole port, or a balanced type of valve may be used, if difficulty in reopening the valve after the hammer has been stopped, should be encountered.

Now the mode of operation of this apparatus may be briefly described. It will be evident that the belt-driven connection above described constitutes a yielding power transmission arrangement, the belting slipping in the event that there is any tendency to transmit an excessive amount of power. Assuming the parts to be arranged as shown in Fig. 1, and with the valve 40 closed, it will be appreciated that as soon as the motor 8 begins to turn over, the pump plunger 11 will begin to reciprocate, and if the cylinder 31 and the connection 3 are filled with liquid, outward movement of the plunger 11 for instance, movement to the left from the position shown in Fig. 3, will produce a partial vacuum in the connection 3, but will not be able, because of the closed position of the valve mentioned, to cause any movement of the piston 32. Inward movement of the pump plunger 11 in its cylinder will simply

result in a relieving of the vacuum, and until the valve 40 is unseated nothing will happen, the pump plunger merely reciprocating and alternating partial vacua, and conditions, so to speak, of normal pressure. If, however, the lever 39 is depressed and the valve 40 opened, there will be established a continuous liquid column extending from the pump plunger 11 to the upper surface of the piston 32, and upon the outward stroke of the plunger 11 there will be produced a condition of reduced pressure such that the piston 32 will follow the liquid column and move to its upper position. Then upon the succeeding stroke of the plunger 11 towards the head of the cylinder 12, the column of liquid will transmit a positive and powerful force to the piston 32 and cause the same to strike a powerful blow. So long as the valve 40 is held off its seat, reciprocation of the plunger 11 will cause forward surges of the liquid column, followed by rearward surges under the action of the pressure to which the forward face of the piston 32 is subjected. That pressure may, of course, be atmospheric pressure, or if appropriate means are provided for permitting ingress but not free egress of pressure to the bore 31 in advance of piston 32, the pressure tending to force the piston rearward may exceed atmospheric pressure. If desired, a spring may be used between the forward face of the piston 32 and the forward end wall of the cylinder 30 to press the piston rearwardly and speed up still more the rearward movements thereof.

With the use of oil as the power transmitting medium, and appropriately grooving and sealing the parts, little air can secure access to the liquid system, but it can be allowed to escape when necessary by removing the plug 26 and then filling the liquid system completely full. Obviously with a given quantity of liquid within the fluid system, an increased amplitude of movement of the plunger 11 will occasion an increased amplitude of movement of piston 32, and accordingly varied strokes of that piston may be made to take place by adjusting the throw of the crank pin 14, varying liquid volume as needed. Obviously either air or water cooling could be provided if long running periods were to make cooling desirable. Free or pressed blows may be had as desired.

It will be evident from the description that has been given, that this apparatus will be highly successful in operation, as well as very efficient in the transmission of power, and a five horsepower motor may be made to produce a net amount of work equal to the work secured from a usual compressor-actuated pneumatic drill having a driving motor of several times as much power. Obviously, the apparatus is extremely simple, subject to virtually no danger of serious derangement, very durable, and effective. Moreover, with the use of oil, perfect lubrication is assured.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In an apparatus of the character described, a fluid-pressure-movable member providing a blow-striking surface, a power-movable member

providing a liquid-column-actuating surface, means for moving said last-mentioned member positively rapidly in opposite directions with a definite stroke, means cooperating with said members totally to enclose and confine in all the relative positions of said members a constant quantity of liquid sufficient to fill the confined space between said members when the same are at corresponding positions in their respective ranges of movement, means for providing a wholly gaseous-pressure-constituted return force for said first mentioned member, an element disposed for actuation by said first mentioned member, and an end-seating reciprocable throttle valve between said members moving on opening towards said first mentioned member. 5

2. In an apparatus of the character described a fluid-pressure-movable member providing a blow-striking surface, a power-movable member providing a liquid-column-actuating surface, means for moving said last-mentioned member positively rapidly in opposite directions with a definite stroke, means cooperating with said members totally to enclose and confine in all the relative positions of said members a constant quantity of liquid sufficient to fill the confined space between said members when the same are at corresponding positions in their respective ranges of movement, means for provid- 10 15 20 25

ing a wholly gaseous-pressure-constituted return force for said first mentioned member, an element disposed for actuation by said first mentioned member, and a reciprocable throttle valve between said members moving on opening towards said first mentioned member. 5

3. In combination, a cylinder containing a reciprocable liquid-column-actuating piston, a cylinder containing a reciprocable blow-striking piston, an implement relative to which said last mentioned piston is reciprocable arranged for actuation by the latter, means providing a liquid conduit connecting said cylinders and coacting with them in confining a quantity of liquid sufficient to fill the space in said conduit and cylinders between said pistons when the latter are in corresponding positions in said cylinders, said second mentioned piston having in its end remote from the connection of its cylinder with said conduit subject only to gaseous fluid pressure, means for rapidly positively reciprocating said first mentioned piston with a predetermined stroke, and a throttle valve openable in the direction of liquid flow toward said second mentioned cylinder and closeable while said first mentioned piston continues to be actuated, to interrupt operation of said second mentioned piston. 10 15 20 25
